UNITED STATES PATENT OFFICE.

ERNEST NITZ, OF PHILADELPHIA, PENNSYLVANIA, ASSIGNOR OF ONE-HALF
TO HENRY THOMSEN, OF SAME PLACE.

MEDICAL INHALER.

SPECIFICATION forming part of Letters Patent No. 268,525, dated December 5, 1882.

Application filed August 19, 1882. (No model.)

To all whom it may concern:

Be it known that I, ERNEST NITZ, a citizen of Bavaria, residing in the city and county of Philadelphia, State of Pennsylvania, have invented a new and useful Improvement in Medical Inhaling Apparatus, which improvement is fully set forth in the following specification and accompanying drawings, in which—

Figure 1 is a vertical section of the inhaling apparatus embodying my invention. Fig. 2 is a top or plan view thereof, partly broken away.

Similar letters of reference indicate corresponding parts in the two figures.

My invention consists of an exterior cylinder and an interior perforated cylinder, between which ice is introduced for cooling said interior cylinder, in combination with a receptacle for the medicament, which communicates with the interior cylinder, and a discharge-pipe, whereby the vapor or volatile matters of the medicament may be cooled and inhaled in a pleasant and agreeable condition.

Referring to the drawings, A represents a closed cylinder, within which is secured a cylinder, B, which is closed at top and bottom, and perforated near the top, as at a.

C represents a medicament-receptacle, which is passed through the top of the cylinder A and connected with the top of the cylinder B, said top being perforated, as at b, at the place coinciding with the base of the receptacle, so that there is communication between the receptacle and cylinder B, the medicament resting on the perforated portion b or a grating within the receptacle above said portion.

D represents a discharge-pipe, which leads from the cylinder B and passes through the wall of the cylinder, its outer end having attached to it a flexible tube, E, which is provided with a mouth or nose piece, F.

The operation is as follows: A quantity of ice is placed in the cylinder A, so as to occupy

a portion of the lower space between the two cylinders A B, the imperforate part of the cylinder B preventing the melted ice or water from entering the cylinder B. Access is had to the cylinder A by means of the removable top of the same, or a chute or other inlet formed in said top or side of the cylinder. The cap or cover of the receptacle is removed and the receptacle supplied with the medicament in a warm or hot state, the cap then being re-applied. The piece F is now fitted to the mouth or nose, and the patient inhales through the same. The vapor, volatile matters, odor, &c., of the medicament are drawn into the cylinder B, where they unite with the cool air, and thus pass through the tube E into the system.

It will be seen that while the vapor, &c., are evolved from warmed or heated medicaments, the temperature of the vapor is reduced, whereby it is made serviceable and pleasant, thus avoiding the disagreeable administering of warm or hot vapor, and increasing the beneficial effect upon the patient, the temperature of the vapor being readily adjusted by the amount of cold air created in the cylinder B.

The piece F has openings c for attachment of a cord, whereby the piece may be readily sustained on the head of the patient.

Having thus described my invention, what I claim as new, and desire to secure by Letters Patent, is—

The cylinder A, in combination with the inclosed cylinder having its upper part perforated and its lower part imperforate, the medicament-receptacle communicating with said inclosed cylinder, and a discharge-pipe, substantially as and for the purpose set forth.

ERNEST NITZ.
